UNITED STATES PATENT OFFICE.

HENRY A. CONSTANTINE, OF NIAGARA FALLS, NEW YORK.

WET-MACHINE.

1,275,394.

Specification of Letters Patent. Patented Aug. 13, 1918.

Application filed August 15, 1916. Serial No. 114,955.

To all whom it may concern:

Be it known that I, HENRY A. CONSTANTINE, residing at Niagara Falls, in the county of Niagara and State of New York, 5 have invented certain new and useful Improvements in Wet-Machines, of which the following is a specification.

This invention relates to improvements in wet machines, and an object thereof is to 10 provide means for automatically removing the sheets of fiber which are accumulated upon the pressure roll.

A more detailed object is to provide means which will bring about a discharge of the 15 sheets of fiber at regular intervals during the operation of the machine, so that said sheets will be of uniform weight and texture.

A more detailed object is to provide means associated with the mentioned pressure roll, 20 preferably adapted to rotate therewith, and constituting a cutter which will be operated to cut longitudinally through the circular band of fiber which has accumulated upon the pressure roll, so that one end of said 25 band will fall by gravity from the roll and thereby facilitate the automatic discharge of the remainder of the band as a sheet as the roll continues to rotate.

Other objects and aims of the invention, 30 more or less specific than those referred to above, will be in part obvious and in part pointed out in the course of the following description of the elements, combinations, arrangements of parts and applications of 35 principles, constituting the invention; and the scope of protection contemplated will be indicated in the appended claims.

In the accompanying drawings which are to be taken as a part of this specification, 40 and in which I have shown a merely preferred form of embodiment of the invention:

Figure 1 is a diagrammatic view illustrating a wet machine with the improvements of this invention incorporated therein.

Fig. 2 is a front elevational view of the 45 pressure rolls, illustrating their supports and portion of one of said rolls being broken away to better disclose the elements constituting this invention;

Fig. 3 is an enlarged detailed end view 50 of the end of the pressure rolls, illustrating the relation of the elements constituting this invention with the pressure rolls,

Fig. 4 is a view similar to that shown in 55 Fig. 3, but the parts are being illustrated in a different position.

Fig. 5 is a fragmentary detailed view illustrating the manner in which the fiber is cut, and

Fig. 6 is an enlarged fragmentary detailed view illustrating a means for effecting adjustment of the cutter.

Referring to the drawings for a detailed description of the structure illustrated therein, the reference character L indicates 65 the frame of the machine, the reference character G indicates the upper pressure roll, and the reference character H indicates the lower pressure roll.

The pressure rolls are mounted in the 70 frame work in the usual manner for receiving an endless belt 1 therebetween, which belt passes over a series of rolls and receives a deposit of wet fiber from a vat 2, the fiber being fed from the vat to the belt by means 75 of a perforated cylinder 3, which hangs within the fiber and engages the outer surface of the belt at its upper side. As the fiber which is deposited upon the outer surface of the belt moves between the rolls G and H, it is picked up by the roll G and forms a thin layer upon said roll. Repeated rotation of the roll causes a thick layer of fiber to be accumulated thereon, as illustrated at 4 in Figs. 3 and 4. When this 80 layer reaches the required thickness, it must be removed from the roll to make room for a repetition of the operation. All of the above is in accordance with the well known 85 operation of machines of this type, and heretofore it has been the custom to have an operator stationed to slit the accumulated roll or band 4 lengthwise with a hand knife whenever he deemed the time proper, so that a portion of the band at one side of the 90 slit will fall downwardly and permit the remainder of the band to be discharged as a sheet by the continued rotation of the roll.

This has resulted in sheets which are not only cut along crooked or uneven lines, but 100 which are also of greatly varying thicknesses.

By employment of the elements now to be described, however, a straight and accurate cut is afforded and the sheets are discharged 105 at regular intervals and of uniform thickness and texture.

Plates or the like 5 and 6 are fixed one to each end of the roll G to rotate therewith. Cutter levers 7 and 8 are carried 110 by said plates respectively, each being pivotally supported, as indicated at 9, so as to

leave fingers 10 projecting a short distance beyond the pivots. The opposite ends of the levers serve to support the opposite ends of a cutter member 11. The cutter member 5 may be of any desired type, but it is preferably formed of small diameter piano wire. Where heavier wire or a different type of cutter is employed, or even where the small diameter wire is employed, the same may be 10 let into a groove in the roll, so that its cutting edge will lie flush with or below the adjacent surface portion of the roll. Where wire is used, a suitable take-up device, as indicated at 12, as shown in Fig. 6 is employed.

The plate 5 extends so as to constitute a positive support for the long ends of the levers 7 and 8 to receive the strain applied to said levers by the tension of the wire. 20 The levers are preferably bent intermediate the ends of the long arms thereof so as to maintain a substantial contact with the surfaces of the plates even during pivotal movement of said arms. 25 An operating bar 13 is arranged beneath the roll G, substantially as indicated, said bar being mounted to slide longitudinally within suitable bearings 14 formed in the frame or supports L. A tension spring 15 is provided for urging the operating bar in a direction toward the right in Fig. 2. A pin or roller 16 is arranged at the left hand end of the bar adapted to engage against the outer surface of a cam wheel 17 which is 30 rotatably mounted upon the adjacent support L. Movement of the bar toward the right is resisted by engagement of the pin with the face of the cam.

A lug or pawl 18 is provided upon the 40 plate 5 disposed to engage suitable ratchet pins or teeth 19 upon the cam wheel 17, so as to cause the cam wheel to rotate the space of one tooth at each complete rotation of the roll G. There may be as many teeth or pins 45 19 as desired for determining the number of rotations which will be completed by the roll G for each rotation of the cam. In fact, the number of teeth may be readily altered at any time, particularly where pins are employed as teeth, by simply inserting or removing one or more pins according to requirements. Obviously other means than removable pins may be employed for accomplishing the same result.

The outer face of the cam 17 is formed 55 with a depression 20 at one point of the periphery thereof adapted to receive the pin 16 upon the completion of each rotation of the cam. When pin 16 falls into the depression 20, the operating bar moves to the right, a distance equal to the depth of the depression and disposes a pair of stop-shoulders 21 and 22 in the path of movement of the finger 10, so that as roll G revolves, the 60 fingers 10 of the levers 7 and 8 come into

engagement with the stop-shoulders 21 and 22 and cause the levers to swing about their pivots and the cutter 11 to bound outwardly away from the surface of the roll.

The stop-shoulders 21 and 22 are preferably adjustably connected to the operating bar, and for the purpose of this adjustment said shoulders are illustrated as comprising separately formed members connected by screws or bolts 23, which extend through slots 24 formed in said members. The shoulders may thus be adjusted to accommodate themselves to slight inaccuracies of adjustment of the other parts, or to take up wear, or for other purposes.

It will of course be understood that the operating bar and the stop-shoulders are arranged in such relation to the roll and the parts carried thereby that they will operate to cause the cutter to move to cutting position at a time when the cutter is in the most appropriate position to facilitate the proper and speedy discharge of the fiber sheet from the roll. This position is clearly indicated in Fig. 4, wherein it will be seen that the portion of the fiber below the cutter is free to fall by gravity away from the roll, so that as the roll continues to revolve, the fiber will be discharged from between the two rolls as a sheet in the usual manner.

It will be further noted that the movement of the cutter outwardly away from the roll assists in freeing the fiber from the roll by giving a certain outward thrust there-to. It will also be noted, especially where a wire cutter is employed, that the flexibility of the wire, and the fact that it is supported only by its opposite ends, will cause the cutting action to begin at the opposite edges of the sheet of fiber and to travel gradually inwardly from said opposite edges toward the middle of the fiber due to the natural bowing of the cutter which will follow. A shearing action is thus afforded which insures a clean and rapid cut.

As many changes could be made in this construction without departing from the scope of the following claims, it is intended that all matter contained in the above description, or shown in the accompanying drawings, shall be interpreted as illustrative only and not in a limiting sense.

Having thus described my invention what I claim as new and desire to secure by Letters Patent is:

1. In a wet machine of the usual type comprising a roll adapted to accumulate a deposit thereon, a flexible cutter carried by said roll, and means for operating said cutter to facilitate discharge of the deposit from said roll in the usual manner.

2. In a wet machine of the usual type comprising a roll adapted to accumulate a deposit thereon, a flexible cutter carried by the roll, and means for causing said cutter

to cut said deposit by a shearing cut to facilitate discharge of the deposit in the usual manner.

3. In a wet machine of the usual type comprising a roll adapted to accumulate a deposit thereon, and flexible means for cutting said deposit by a shearing cut.

4. In a wet machine of the usual type comprising a roll adapted to accumulate a deposit thereon, a flexible cutter, supports therefor at opposite ends of the roll, and a member arranged adjacent to the roll adapted to operate simultaneously upon the supports to move the cutter to cutting position.

15 5. In a wet machine comprising a roll adapted to accumulate a layer of material thereon, and flexible shearing means controlled by said roll for effecting the discharge of said layer at the end of a predetermined number of revolutions of said roll.

6. In a wet machine comprising a roll adapted to accumulate a layer of material thereon, a flexible cutter for cutting said layer, and means for adjusting said cutter.

25 7. In a wet machine comprising a roll

adapted to accumulate a layer of material thereon, a cutter for cutting said material, and said cutter comprising a wire carried by said roll beneath said layer adapted to be moved outwardly through said layer. 30

8. In a wet machine comprising a roll adapted to accumulate a layer of material thereon, a cutter for cutting said material comprising a flexible element carried by the roll beneath said layer, and means engaging the opposite ends of said flexible element to move the same through said layer. 35

9. In a wet machine comprising a roll adapted to accumulate a layer of material thereon, a cutter for cutting said layer comprising a flexible member interposed between the roll and said layer, and means to cause said cutter to cut said layer by a shearing cut. 40

In testimony whereof, I affix my signature in the presence of two witnesses.

HENRY A. CONSTANTINE.
